UNITED STATES PATENT OFFICE.

HERMAN GREEN, OF NEW YORK, N. Y.

DESIGN FOR CORD.

SPECIFICATION forming part of Design No. 27,365, dated July 13, 1897.

Application filed April 8, 1897. Serial No. 631,321. Term of patent 14 years.

To all whom it may concern:

Be it known that I, HERMAN GREEN, a citizen of the United States, residing in the city of New York, in the county and State of New York, have invented a certain new and original Design for Cord, of which the following is a specification, reference being had to the accompanying drawing, forming a part hereof.

My invention relates to a design for cord such as commonly employed for making button-loops of waistbands and for other like purposes; and it consists in the shape and configuration of the cord, substantially as shown in the accompanying drawing, which represents in side elevation a short section of the cord which embodies my design.

Referring particularly to the drawing, it will be seen that the body of the cord is substantially cylindrical, as at *a*, and that along

one side is a series of protuberances *b b*, at substantially regular intervals, with intervening depressions *c*. A band *d* crosses the cord at regular intervals, corresponding with the depressions *c*, being obliquely disposed, as shown in side elevation, but being a continuous spiral when the cord is viewed on all sides.

What I claim, and desire to secure by Letters Patent, is—

The design for cord substantially as shown and described.

This specification signed and witnessed this 6th day of April, A. D. 1897.

HERMAN GREEN.

In presence of—

WILFRED J. BELL,
P. GREEN.
